UNITED STATES PATENT OFFICE.

WILLIAM E. LEIBING, OF SAN FRANCISCO, CALIFORNIA.

DESIGN FOR A BUILDING.

Application filed January 14, 1929. Serial No. 29,601. Term of patent 14 years.

To all whom it may concern:

Be it known that I, WILLIAM E. LEIBING, a citizen of the United States, residing at San Francisco, in the county of San Francisco and State of California, have invented a new, original, and ornamental Design for Buildings, of which the following is a specification, reference being had to the accompanying drawing, forming a part thereof.

Figure 1 is a perspective view of the building.

Figure 2 is a diagrammatic top plan view thereof.

I claim:

The ornamental design for a building as shown.

WILLIAM E. LEIBING.
